CLAIM

The ornamental design for a liquid dispensing station as shown and described.

DESCRIPTION

FIG. 1 is a top, right, exploded, perspective view of a liquid dispensing station according to our new design.

FIG. 2 is a perspective view of a shelf component for our design.

FIG. 3 is a top view thereof.

FIG. 4 is a bottom view thereof.

FIG. 5 is a right side elevational view thereof.

FIG. 6 is a left elevational view thereof.

FIG. 7 is a rear elevational view thereof.

FIG. 8 is a front elevational view thereof.

FIG. 9 is a perspective view of a pad component for our design.

FIG. 10 is a top view thereof.

FIG. 11 is a bottom view thereof.

FIG. 12 is a left end view thereof.

FIG. 13 is a right end view thereof.

FIG. 14 is a front view thereof.

FIG. 15 is a rear view thereof.

FIG. 16 is perspective view of a shelf component for our design.

FIG. 17 is a top view thereof.

(Continued)

FIG. 18 is a bottom view thereof.
 FIG. 19 is a left side view thereof.
 FIG. 20 is a right side view thereof.
 FIG. 21 is a front side view thereof.
 FIG. 22 is a rear side view thereof.
 FIG. 23 is a perspective view of a pedal component for our design.
 FIG. 24 is a top view thereof.
 FIG. 25 is a bottom view thereof.
 FIG. 26 is a right side view thereof.
 FIG. 27 is a left side view thereof.
 FIG. 28 is a front side view thereof.
 FIG. 29 is a rear side view thereof.
 FIG. 30 is a perspective view of a rod component for our design.
 FIG. 31 is a right side view thereof.
 FIG. 32 is a left side view thereof.
 FIG. 33 is a first lengthwise view thereof.
 FIG. 34 is a second lengthwise view thereof.
 FIG. 35 is a third lengthwise view thereof.
 FIG. 36 is a fourth lengthwise view thereof.
 FIG. 37 is a perspective view of a strap component for our design.
 FIG. 38 is a folded edge end side view thereof.
 FIG. 39 is an open-ended side view thereof.
 FIG. 40 is a first side view thereof.
 FIG. 41 is a second side view thereof.
 FIG. 42 top view thereof.
 FIG. 43 is a bottom view thereof.
 FIG. 44 is a perspective view of a support component for our design.
 FIG. 45 is a first side view thereof.
 FIG. 46 is a second side view thereof.
 FIG. 47 is a rear view thereof.
 FIG. 48 is a front view thereof.
 FIG. 49 is a top view thereof.
 FIG. 50 is a bottom view thereof.
 FIG. 51 is a front perspective view of wall panels of a liquid dispensing station, shown in an open, unassembled configuration.
 FIG. 52 is a front elevational view thereof.
 FIG. 53 is a rear elevational view thereof.
 FIG. 54 is a left side elevational view thereof.
 FIG. 55 is a right side elevational view thereof.
 FIG. 56 is a top view thereof.
 FIG. 57 is a bottom view thereof.
 FIG. 58 is an enlarged view of portion 58 shown in FIG. 52.
 FIG. 59 is an enlarged view of portion 59 shown in FIG. 53.
 FIG. 60 is a perspective view of wall panels, shown in a partially folded configuration.
 FIG. 61 is a front side view thereof.
 FIG. 62 is a rear side view thereof.
 FIG. 63 is a left side view thereof.
 FIG. 64 is a right side view thereof.
 FIG. 65 is a top side view thereof.
 FIG. 66 is a bottom side view thereof.
 FIG. 67 is an enlarged view of portion 67 shown in FIG. 61.
 FIG. 68 is an enlarged view of portion 68 shown in FIG. 62.
 FIG. 69 is a top, right, front perspective view of a liquid dispensing station, shown in an assembled configuration.
 FIG. 70 is a front elevational view thereof.

FIG. 71 is a rear side elevational view thereof.
 FIG. 72 is a left side elevational view thereof.
 FIG. 73 is a right side elevational view thereof.
 FIG. 74 is a top view thereof.
 FIG. 75 is a bottom view thereof; and,
 FIG. 76 is an enlarged view of portion 76 shown in FIG. 69. The broken lines shown in the drawings illustrate portions of the liquid dispensing station that form no part of the claimed design. The dash-dot-dash broken lines represent boundaries of the claim as well as the designation of enlargement views and form no part of the claimed design.
